ABSTRACT

Molten metal is forced upwardly by bottom pressure casting through an ingate and into the casting cavity of a mold having a dam to retain the metal in the cavity after the ingate has been drained. The mold is preferably formed from separable graphite cope and drag sections and may include an outer cast iron chill ring to impart the desired outer contour to the casting with accuracy. A plurality of such molds may be stacked and filled in one pouring operation.

APPARATUS FOR CASTING MOLTEN METAL

BACKGROUND OF THE INVENTION

1. Field of the Invention

This invention relates to a method and apparatus for casting molten metal and more particularly to a bottom pressure casting operation wherein molten metal is forced upward by the application of superatmospheric pneumatic pressure into a mold where the metal solidifies or partially solidifies.

2. Description of the Prior Art

After the casting cavity of the mold is filled in a bottom pressure casting operation, means must be employed to retain the metal in the mold until the desired degree of solidification has occurred, in order to prevent the metal from returning to the ladle. The various methods that have been employed for this purpose have included constant pressure systems and mechanical valve devices.

The constant pressure system employs a suitable valve arrangement in conjunction with the pneumatic pressure source to maintain the pressure on the molten metal constant at a level required to retain the metal in the mold. One type of mechanical arrangement includes a refractory stopper in the ingate of the mold, which is closed upon completion of the pouring operation. Another mechanical device comprises a horizontal slide having an open position during the pouring operation and movable to a closed position after the casting cavity has been filled.

While the above mentioned methods have been found to be effective and commercially successful, they are not readily adaptable to the production of certain shapes, such as those having a central void. The use of a stopper or slide may necessarily cause entrapment of the metal in the central portion of the casting cavity as well as in its outer periphery, requiring the later removal of the central solidified metal to produce a finished product. Since the entrapment of excess metal is detrimental to a high yield, it is highly desirable, if possible, to initially cast the article in its substantially finished or final shape.

Accordingly, an object of this invention is to provide a method and apparatus for casting articles by bottom pressure casting that does not employ mechanical means or pneumatic pressure means to retain the molten metal in the mold upon completion of the pouring operation.

Another object of this invention is the provision of a novel mold structure which retains substantially only that molten metal needed to form the desired casting.

SUMMARY OF THE INVENTION

The above objects are accomplished by means of a weir or dam in the casting cavity, which retains metal therein but allows excess metal to return to the ladle upon relieving pressure to the tank. A novel mold construction is also employed, utilizing interchangeable intermediate mold sections to form a plurality of mold cavities.

BRIEF DESCRIPTION OF THE DRAWING

FIG. 1 is a vertical sectional view of a bottom pressure casting apparatus that incorporates features of the presently described invention; and

FIG. 2 is a plan view of the cast iron contour ring used in the mold shown in FIG. 1.

DESCRIPTION OF THE PREFERRED EMBODIMENT

With more particular reference to the drawing, the apparatus for bottom pressure casting shown in FIG. 1 comprises a ladle, generally indicated at 10, having an inner refractory lining 12 and an outer metallic shell 14, said ladle being disposed within a pressure tank 16. A cover 18 having suitable insulation 20 on the inner side thereof is releasably clamped on the pressure tank 16 by means of a suitable clamping device, generally indicated at 22, and is sealed to the tank by an annular resilient seal 21 therebetween. As shown, the

clamping device 22 may include a lever 24 pivotally suspended from the edges of the cover 18. A hydraulic or pneumatic ram 26 may be mounted upon the tank supporting framework 28 to engage an arm 23 of the lever 24 in a downward direction. A roller 25 may be mounted on the lever 24 to be engageable with a flat vertical guide plate 27 secured to the tank 16.

A refractory pouring tube 30 is disposed centrally within the ladle 10 with its lower end 31 proximate the bottom of the ladle and its upper end 33 extending through and above the cover 18 and secured to an adapter 32 sealed to the cover. The tank 16 is thus substantially sealed, such that application of superatmospheric pressure thereto from a suitable source, such as that indicated at 34, connected to the tank will cause the molten metal 36 to rise upward in the pouring tube 30 to fill the mold 40.

The upper portion of the adapter 32 is flared outward at 38 to receive a female member 42 of the mold assembly, generally indicated at 40. The mold assembly 40 is composed of a chill material, such as graphite, and comprises an upper or cope section 44 and a lower or drag section 46, which in turn communicates with an ingate 48 formed centrally therein. The mating surfaces of the cope and drag sections are machined or formed to together define a casting cavity such as 50 therebetween, with a common central passageway 52 in communication with the ingate 48 for the admission of molten metal from the ladle 10. The passageway 52 in the cope section 44 extends upward and is open to the atmosphere.

As shown in FIG. 1, the mold assembly 40 may also comprise one or more intermediate and interchangeable mold sections 54 between the cope 44 and drag 46 sections, the purpose of which is to form additional casting cavities. It may be seen that the underside of each intermediate mold section 54 is adapted to serve as the cope section for the mating mold section located therebelow, while the upper side is adapted to serve as a drag section for the mating section thereabove, thereby defining a series of casting cavities in a vertically spaced relationship. The intermediate sections 54 and the cope and drag sections, 44 and 46, respectively, are mounted within suitable frame members 60, and retainers 62 are provided between adjacent frame members to hold the mold sections in an assembled relationship. When assembled, the mold 40 is designed such that the ingate 48 thereof is in register with the bore 64 of the pouring tube 30.

A groove 66 is formed near the outer periphery of each drag section surface to retain a flange 68 depending from a contour insert member 70. One possible configuration of such a member is shown in FIG. 2, which may include a round outer surface 71 and an inner contoured surface 72 of any desired shape, such as the sprocket contour shown. The insert member 70 is preferably composed of cast iron to insure accurate contours with repeated usage, but other chill materials, such as graphite, may sometimes be employed.

As shown in FIG. 1, an annular continuous dam or weir 74 is provided as part of each drag section of the mold around the central passageway 52 or ingate 48, as the case may be. The apex 76 of each weir 74 extends upward for a height equal to or above the height of the casting cavity 50, and each adjacent cope section is suitably contoured, such as at 78 to accommodate the weir. Refractory cores 80 may be inserted between adjacent cope and drag sections, in order to impart apertures to the casting. Suitable vent holes 82 communicating with the atmosphere at 84 and 85 may be provided within the graphite mold sections 44, 46 and 54 above and below and communicating with the refractory cores 80. The cores 80 are preferably composed of a zircon sand bonded by a resin material or other suitable ceramic material and are designed to seat in the lower vent hole.

It should be noted that the ingate 48 is lined with a ceramic material throughout substantially the entire length of the mold. This feature prevents freezing of the metal in the mold during the casting operation and allows the metal to drain freely from the ingate 48, as described below.

In operation, the ladle 10 is filled with molten metal 36, placed in the tank 16, and the cover 18 is applied and sealed by actuation of the ram 26 of the clamping device 22. Pressure is then applied to the tank 16 from pressure source 34, which causes the molten metal to rise upward through the bore 64 of the pouring tube 30 and fill each of the casting cavities 50. After the mold has been filled, the pressure in the tank 16 is relieved by opening a suitable valve 86 connected thereto, thereby causing all excess metal in the passageway 52 and the ingate 48 to be returned to the ladle 10. It may be seen that each casting cavity 50 serves as a receptacle with the weir 74 preventing return of metal in the cavity. Preferably, the mold is designed to retain sufficient metal in the casting cavity 50 in order to accommodate volume contraction of the metal upon solidification. While some metal may have to be removed by machining from the central portion of the casting, it may be seen substantially only that metal which is needed to produce the final product is retained.

I claim:

1. An apparatus for casting molten metal comprising a mold having an upper section and a lower section, said upper and lower sections mating with one another and formed to define a casting cavity therebetween, ingate means in said mold for communication between said casting cavity and a source of molten metal, means for moving said molten metal into said ingate means to fill said casting cavity, drain means in a lower portion of said mold for draining molten metal away from said casting cavity, weir means vertically surrounding said drain means for retaining molten metal up to the intended height of the casting in said casting cavity upon the filling thereof, a plurality of bonded refractory cores between said upper and lower sections within said casting cavity, and vent means extending from said cores to the exterior of said mold.

2. An apparatus for casting molten metal comprising an upper section, a lower section, a plurality of interchangeable mold sections engaged with one another and located between said upper section and said lower section, said mold sections

together with said upper section and said lower section extending in a generally upward direction and defining therebetween a plurality of annular casting cavities, a plurality of refractory cores in said casting cavities, vent means connecting certain of said cores to the exterior of said casting cavities, a common upwardly extending passageway centrally located relative to said annular casting cavities and in fluid communication with each of said casting cavities through an annular opening, an ingate located in said lower section, said ingate being in fluid communication with said passageway, a plurality of annular continuous weirs around said central passageway, each of said weirs being located adjacent to one of said openings to each of said casting cavities and having a circular apex extending upwardly to a height above the uppermost portion of the respective casting cavity, means to force molten metal upwardly through said ingate into said passageway over the circular apex of each of said weirs to fill each of said casting cavities, and means to remove said molten metal from said passageway whereby said weirs will retain molten metal in said casting cavities.

3. The apparatus set out in claim 2 wherein said means to force molten metal comprises a vessel filled with molten metal located below said lower section, an upwardly extending tube communicating with said molten metal and said ingate means, means to exert pressure on said molten metal in said vessel to force molten metal upwardly through said tube into said ingate means and said passageway and wherein said means to remove said molten metal comprises means to reduce said pressure on said molten metal to allow said molten metal in said passageway and said ingate means to return to said tube.

4. The apparatus set out in claim 2 wherein certain of said cores are located along an upwardly extending line through said cavities, and said vent means includes an upwardly extending tube between said cores along said line, said tube being partially defined by a portion of said upper section and by portions of said mold sections.
